Primary Examiner — R. Johnson(74) *Attorney, Agent, or Firm* — Westman, Champlin & Koehler, P.A.(57) **CLAIM**

The ornamental design for a snare throw off, as shown and described.

DESCRIPTION

FIG. 1 is a perspective view of the snare throw off; FIG. 2 is another perspective view of the snare throw off; FIG. 3 is a front elevational view of the snare throw off; FIG. 4 is a rear elevational view of the snare throw off; FIG. 5 is a left side view of the snare throw off; FIG. 6 is a right side view of the snare throw off; FIG. 7 is a top view of the snare throw off; FIG. 8 is a bottom view of the snare throw off; FIG. 9 is an environmental perspective view of the snare throw off on a drum; and, FIG. 10 is another environmental perspective view of the snare throw off on a drum. The broken lines of the FIGS. form the bounds of the claimed design, or are included for the purpose of illustrating environmental structure, and form no part of the claimed design. The boundary line indicates that the claimed portion of the design stops thereat.
